UNITED STATES PATENT OFFICE.

HERBERT R. BLISS, OF NIAGARA FALLS, NEW YORK, ASSIGNOR TO BLISS CONTAINERS, INC., OF NIAGARA FALLS, NEW YORK, A CORPORATION OF NEW YORK.

SHIPPING CASE.

Application filed January 9, 1924. Serial No. 685,097.

This invention relates to a shipping case constructed of fibre board or equivalent material. It is the custom now for the trade to use either a slotted end container or else a recessed end container. However, there has recently been introduced the flush-end three-blank container such as shown in my Patents No. 1,452,588 and No. 1,875,127. These containers, known as the Bliss Nos. 2 and 4, are making rapid strides in supplanting the slotted end container and the recessed end container for the reason that they are more economical containers in the way of material required to make them and are much stronger and more desirable than the recessed end container.

However, a container of this three-blank type, in order to get the best results in labor economy in setting it up, requires the use of an expensive stitching machine which will simultaneously stitch both the end blanks on each end. Small shippers do not feel warranted in undertaking the expense of the installation of the double-headed stitcher. It is the object of the present invention to provide a shipping case which has nearly all the advantages of the Bliss Nos. 2 and 4 boxes, and yet eliminates the necessity of a double head stitcher in setting up and sealing the case.

Furthermore, the case is a two-blank case in which the blanks may be sewed together at the mill on a double head stitcher so the shipper has a complete box all sewed together ready to set up. This is a great advantage in handling, in the case of small shippers.

In the drawings:

Fig. 1 is a plan view of one of the blanks of the end loader.

Fig. 2 is a plan view of the other blank of the end loader.

Fig. 3 shows this case set up and in process of sealing.

Figs. 4, 5, 6, 7, 8, 9 and 10 are sections taken on the corresponding section lines of Fig. 3.

Fig. 11 is a perspective of a side loader, or what is sometimes called a top loader, but which involves the same invention.

Figs. 12 and 13 are sections taken on the corresponding section lines of Fig. 11.

Fig. 14 is a perspective of the top loader before sealing.

Fig. 15 is a perspective of the end loader before sealing.

Figs. 16 and 17 are plan views of the two blanks of the top loader.

Referring to Figs. 1 and 2, it will be seen that two blanks are employed, each comprising three walls so that the two blanks form the necessary six walls of the case. Three of the side walls *a*, *b* and *c* are formed by what I call the major blank. The other side wall *d* and the two end walls *e* and *f* are formed by the other blank, which I term the minor blank. In the recessed end case and in the slotted end container, the four walls of the main blank are sewed together in a collapsible tube by what is known as a manufacturer's seam. I propose to have my case sewed together in a collapsible tube in the same way but two manufacturers' seams are required. These are formed by the two manufacturers' seam flaps *g* and *h*, which are preferably on the major blank (so that the tube may be stitched by a double head stitcher) but which could obviously be on the side of the wall *d* of the minor blank but if here located would result in considerable waste of material and would not be stitched by a double head stitcher. The mill can stitch the manufacturers' seam flap *h* and *g* to the side wall *d* as shown in Fig. 5; this will make a collapsible tube having the two end walls *e* and *f* permanently secured thereon and which can be secured in place by the aid of the flaps *a*, *b*¹, and *c*¹, and *a*², *b*² and *c*².

No difficulty will be found in sewing the first end wall *f* to the flaps *a*², *b*² and *c*² as shown in Figs. 4 and 5; this can be easily done with any form of straight anvil that can be inserted in the end of the box. The end flaps may be secured on the inside or outside; this is a matter of indifference. It will be noticed, however, that only three flaps have to be stitched in place as compared with four flaps on the recessed end box and on the Bliss No. 2 and No. 4 boxes. The reason for this is that the end blank is already integrally united with one of the side walls.

In Fig. 3, I have indicated how the case

may be sealed. The end flap b^1 is turned in under the end blank e . A blade anvil k is then inserted and the stitches 1, 2, 3 and 4 are taken to unite the end wall e with the flap b^1 , care being taken to take stitch 1 far enough away from the corner to permit the blade anvil to be inserted in position k^1 , shown in the drawings. The flap a^1 may be turned in on the inside or it may be on the outside of the end wall e ; stitches 5, 6, 7, 8 and 9 are taken with the aid of the blade anvil in the position designated k^2 . These two positions k and k^2 of the blade anvil require only one insertion and withdrawal of the anvil so that they are practically one. The case may then be swung around and with the anvil inserted in the position shown at k^1 , the stitches 10, 11, 12, 13 and 14 may be taken through the flap a^1 and end wall e with the flap a^1 either on the inside or on the outside of the end wall. This completes the sealing of the case.

When the case is completed, the amount of stitching that has been required by the shipper is no more than required for the well known slotted end container, yet the saving in material over the slotted end container is relatively greater, depending of course, upon the dimensions of the box; it will approximate somewhere in the neighborhood of 20%. The case in its final form has flush ends 270 degrees on the outside and 90 degrees on the inside with clear corners, thus obviating many objections connected with the recessed end case.

In Figs. 11 to 14 inclusive and 16 and 17 I have shown a top or side loader. Here the minor blank contains two side walls m and n at its ends, while the major blank has two side walls o and p at its end. The end walls q and r are with the top loader in the middle of the minor and major blanks. The flaps o^1, q^1, p^1, o^2, q^2 and p^2 are the securing flaps. The manufacturers' seam flaps s and t are not as long for a box of the same dimensions. However, the box is set up and sealed in practically the same way as is shown in Figs. 11 and 12.

It will be seen that the essence of the invention is a shipping case having flush ends made up of two separate blanks of three walls each that can be made up in the form of a collapsible tube by two manufacturers' seam flaps, and which is provided then with two foldable integral bottom and top walls that may be secured flush in the ends of the tube by shallow flaps. In order to avoid confusion in the claims, I am going to refer to the portions of the case that are first

stitched together in setting the tube up as the bottom, to the final parts that are stitched together to seal the case as the top.

It will be understood that where the term "major and minor" blanks is used in the claims that the term "major" blank refers to that part of the blank which is known as the body blank, or the part forming the sides and the end, or ends and side; while the term "minor" blank refers to that blank which forms an end or side and the top and bottom. More specifically, and referring to a two-blank case of the collapsible type, the major blank is that blank which forms the three sides of the collapsible case, while the minor blank forms the one side and the cover wings for the top and bottom or the two ends, according to the particular type of case.

What I claim is:

1. A shipping case of fibre board, or equivalent material, of a type having two blanks each of three walls secured together to form a collapsible tube with foldable top and bottom walls, comprising a major blank forming three of the side walls, each end of said major blank being provided with an integral manufacturer's seam flap and one end of each of the three side walls of said blank provided with integral shallow sealing flaps and a minor blank forming a side wall and the foldable top and bottom walls, the manufacturer's seam flaps on the ends of the major blank being secured to the center wall of the minor blank.

2. A shipping case of fibre board, or equivalent material, of a type having two blanks secured together to form a collapsible tube with foldable top and bottom walls, comprising a major blank forming three of the side walls, each end of said major blank being provided with an integral manufacturer's seam flap, and one or more of the three side walls of said blank being provided with an integral sealing flap, and a minor blank having a plain wall for completing the fourth side wall and an integral cover flap for closing the top or loading end of the case, two of the side walls of the major blank being positioned against the side wall of the minor blank, and the manufacturer's seam flaps on the ends of the major blank being folded within and parallel to the plane of the side wall of the minor blank whereby the manufacturer's seam flaps may be simultaneously stitched to form a collapsible tube ready for shipping.

In testimony whereof I have affixed my signature.

HERBERT R. BLISS.
